United States Patent Office

Des. 221,635
Patented Aug. 31, 1971

221,635

TRAILER CAMPER OR SIMILAR ARTICLE

Richard J. Makela, 332 N. Valeria,
Santa Maria, Calif. 93454

Filed July 17, 1970, Ser. No. 24,007

Term of patent 14 years

Int. Cl. D12—10

U.S. Cl. D14—3

FIG. 1.

FIG. 2.

FIG. 1 is a perspective view showing the front, top and one side of a trailer camper incorporating my new design, and,

FIG. 2 is a rear perspective view of a trailer camper incorporating my new design, showing the rear and top thereof and the side thereof opposite that shown in FIG. 1.

I claim:

The ornamental design for a trailer camper or similar article, substantially as shown.
